UNITED STATES PATENT OFFICE.

JONATHAN EVANS, OF PHILADELPHIA, PENNSYLVANIA, ASSIGNOR OF ONE-HALF TO DAVID H. BURRELL, OF LITTLE FALLS, NEW YORK.

CENTRIFUGAL SEPARATOR.

SPECIFICATION forming part of Letters Patent No. 360,342, dated March 29, 1887.

Application filed March 10, 1886. Serial No. 194,705. (No model.)

To all whom it may concern:

Be it known that I, JONATHAN EVANS, of the city of Philadelphia, in the county of Philadelphia and State of Pennsylvania, have invented new and useful Improvements in Centrifugal Separators, of which the following is a specification.

My invention relates to a centrifugal separator which consists of a separating-drum secured to an upright spindle, which latter is mounted in a suspended frame in such manner that the frame is free to assume a perpendicular or more or less inclined position in adjusting itself to the center of gravity of the revolving system.

The principal object of my invention is to produce a machine of this kind which is adapted for creaming milk by centrifugal force.

My invention consists of the improvements which will be hereinafter fully described, and pointed out in the claims.

In the accompanying drawings, Figure 1 is a sectional elevation of a centrifugal separator provided with my improvements. Fig. 2 is a sectional elevation at right angles to Fig. 1. Fig. 3 is a top plan view of the machine. Fig. 4 is a horizontal section in line x x , Fig. 1.

Like letters of reference refer to like parts in the several figures.

A represents the separating drum or basket, and B the vertical spindle to which the drum is secured. The machine represented in the drawings is designed for separating a compound liquid into its constituent liquids of different specific gravities, and the drum employed in this machine is therefore made tight or imperforate. The spindle B is provided at its lower end with a step, b, and near its upper end with a journal, b'.

C represents a pulley or band-wheel secured to the upper end of the spindle for imparting motion to the same.

D represents the movable or self-adjusting frame, in which the spindle B is journaled. The frame embraces the separating-drum and is provided below the drum with a step-bearing, d, in which the step b of the spindle rests. The upper end of the frame D is provided

with a bearing, d', in which the journal b' of 50 the spindle turns.

F represents a spherical knuckle or journal formed at the upper end of the frame D, and G represents a concave bearing which receives the knuckle or bearing F, so that the frame D and the parts supported therein are suspended by means of the knuckle F in the bearing G. The latter is composed of a conical ring, f, which is secured to a wall-bracket, H, or other suitable stationary support. The upper bearing, d', of the spindle is secured in the knuckle F, into which it is inserted through an opening formed in the top of the knuckle.

i represents a drip-cup secured to the spindle B below the bearing d', and I represents an annular collecting-trough, which is attached to the bearing G, and which surrounds the drip-cup i and collects the oil or other material which is thrown out of the same by the centrifugal force.

The knuckle F is provided with a lug, f', which strikes against a lug, f'', on the bearing G, and whereby the frame D is prevented from rotating with the spindle by frictional contact.

The bracket H can be secured directly to the posts of the spring-house or other building in which the separator is placed. It avoids the cost of special foundations, and does not obstruct the floor-space. The spherical knuckle F is located in the upper portion of the frame D, and the point of support on the under side of the knuckle is located within the frame, thereby affording a steady and reliable support for the frame and drum.

K represents the feed-pipe by which the liquid to be separated is fed into the drum A. This pipe is attached to the frame D on one side of the spindle B, and provided at its inner end with a removable nozzle, k, which depends into the drum and delivers the liquid upon the bottom of the same near the center. The feed-pipe is also preferably provided with a stop-cock, l, for regulating the feed. The outer end of the feed-pipe is connected with the supply-pipe or reservoir by a flexible connection, which may be a section of india-rubber pipe, so that the proper connection of the

feed-pipe K with the supply-pipe or reservoir is maintained in the various positions of the frame D.

- M is the discharge or skimming pipe, 5 through which the heavy separated liquid is discharged from the drum. When the machine is used for creaming milk, full milk is fed into the drum through the pipe K and the skim-milk is discharged through the pipe M.
- o The discharge-pipe M is attached to the frame D preferably diametrically opposite the feed-pipe, and is preferably made adjustable on the frame, so that its curved inner end can be nicely adjusted, in order to properly remove 5 the heavy liquid from the drum. The discharge-pipe M delivers the heavy liquid to any suitable receptacle.

N represents the discharge-pipes through which the light liquid is discharged from the

- o drum. As shown in the drawings, the discharge-pipes N penetrate the bottom of the drum and discharge the light liquid into an annular collecting-trough, O, which is secured to the frame D below the drum. When the machine is used for creaming milk, the cream is discharged from the drum through the discharge-pipes N into the trough O, from which latter the cream flows through a discharge-pipe, p, into a suitable receptacle.
- o The trough O is divided into halves, diametrically or radially, and each half is provided with tapering lugs o', projecting outwardly on both sides of the frame D. The two halves are drawn together by loops o'', which engage over the tapering lugs o', and screws o', which are secured to the frame. In order to produce a tight joint between the halves a suitable packing, o⁴, of rubber or other suitable material, is placed between the contiguous faces of the parts. This construction permits the removal of the trough O without disturbing the spindle.

Q represents an annular shield or curb, which is secured to the frame D and surrounds 5 the drum A.

Upon rotating the spindle B and drum A by means of an endless belt running around the pulley C, and feeding the liquid or other material to be separated into the drum, the

- o frame D adjusts itself by means of the knuckle F and bearing G as may be necessary to establish an equilibrium of the rotating parts; hence, if the center of gravity of the rotating system should be out of center from any cause, 5 the automatic adjustment of the frame D will compensate for this defect and avoid all injurious effects upon the machine.

In centrifugal creamers it happens occasionally that the drum becomes unbalanced

- o by reason of an unequal deposit of solid sediment upon the inner surface of the drum. In ordinary machines, in which the spindle is supported in fixed bearings, this would cause the machine to run untrue and produce various injurious effects, such as excessive and 5 unequal wear of the bearings, imperfect separa-

ration of the milk, and consequent loss of cream, while it also increases the danger of bursting the drum. The automatic adjustment of the frame D avoids these difficulties, 70 and causes the machine to run properly under all circumstances. This renders it unnecessary to balance the machine as perfectly as an ordinary machine running in fixed bearings, which operation consumes much time and requires great skill, and a machine of the character herein described is therefore produced at less expense, thereby rendering the present construction especially desirable for small machines intended to be placed within the reach 80 of farmers of small means.

The devices for feeding the drum and discharging the products of the separation therefrom may be modified in many ways, which will be obvious to persons skilled in the construction of centrifugal creamers and other similar separating machines.

I am aware that a drum-supporting frame suspended by a spherical knuckle and connected at its lower end to supports by elastic 90 connections is not new in centrifugal machines, and I do not claim the same.

I claim as my invention--

1. The combination, with the spindle and separating-drum, of a frame provided at its 95 upper and lower ends with bearings in which the spindle is journaled, a universal joint by which the upper end of the frame is suspended, while the lower end of the frame is free and capable of lateral movement, and feed and discharge pipes attached to the suspended frame and supplying and removing liquid to and from the drum, substantially as set forth.

2. The combination, with the spindle and separating-drum, of a frame provided at its 105 upper and lower ends with bearings in which the spindle is journaled, a universal joint by which the upper end of the frame is suspended, while the lower end of the frame is free and capable of lateral movement, and a feed-pipe, K, 110 a skimming-pipe, M, and a collecting-trough, O, attached to the suspended frame, substantially as set forth.

3. The combination, with the frame provided at its upper and lower ends with bearings and at its upper end with a spherical suspending-knuckle, of a spindle journaled in said bearings and passing through the spherical knuckle, a pulley secured to the spindle above the knuckle, and a drum secured to the 120 spindle within the frame, substantially as set forth.

4. The combination, with the spindle and the separating-drum secured to the same, of a self-adjusting suspended frame provided above 125 and below the drum with journals in which the spindle is supported, and an annular shield or curb surrounding the drum and frame and secured to the outer side of the latter, substantially as set forth.

5. The combination, with the drum, the spindle, and the frame in which the spindle

is journaled, of an annular collecting-trough surrounding the spindle and composed of separable parts, whereby the trough can be removed without disturbing the spindle, substantially as set forth.

5 6. The combination, with the drum, spindle, and the supporting-frame D, of the annular trough O, composed of separable parts, provided with tapering lugs o', loops o², and

screws o³, whereby the parts are secured together, substantially as set forth.

Witness my hand this 5th day of March, 1886.

JONATHAN EVANS.
